LLP**CLAIM**

The ornamental design for a building glass, as shown and described.

DESCRIPTIONFIG. 1 is a perspective view of a building glass;
FIG. 2 is a second perspective view of the building glass;and,
FIG. 3 is a third perspective view of the building glass.
The broken lines in FIG. 1 illustrate the boundaries of the
claimed design. The glass body is constructed of a translu-
cent material that at least partially blurs an object that is
located behind the glass body to a viewer looking through
the glass body. Additional broken lines in FIGS. 2 and 3
illustrate the boundaries of FIGS. 2 and 3.**1 Claim, 3 Drawing Sheets***FIG. 1*
